FOLDING EXTENSION TABLE

Alpha O. Hendricks, Manistee, Mich.

Application July 10, 1935, Serial No. 30,706

5 Claims. (Cl. 311—97)

My invention relates to improvements in tables, particularly, folding extension tables.

The primary object of my invention is to provide a table adapted for a wide range of adjustments as regards both length and height so that it is especially adapted for use on uneven ground and which is foldable into compact boxlike form for transportation or storage to conceal the legs to present a neat outside appearance.

10 Another object is to provide a table equipped with telescopic legs of metal hinged to the table for folding thereunder and substantially enclosed when the table is folded so that they are practically concealed from view.

15 Other objects are to provide a table of the above specified type which is strongly constructed, readily folded, and unfolded, and in which all parts are securely held in either their folded or unfolded positions.

20 Still other and subordinate objects will appear when the following description and claims are read with reference to the drawings accompanying and forming a part of this specification.

In said drawings:

25 Figure 1 is a view in end elevation of a table constructed according to my invention, parts being broken away and being shown in section, and the table being shown in unfolded position.

Figure 2 is a view in end elevation illustrating 30 the table as it appears when folded.

Figure 3 is a view in vertical longitudinal section taken on the line 3—3 of Figure 1 looking in the direction indicated by the arrows, the parts being shown in unfolded position.

35 Figure 4 is a view similar to Figure 3 with the table parts shown in folded position.

Figure 5 is a view in top plan of one of the legs of the table.

Figure 6 is a view in side elevation of a blank 40 from which a part of the table leg is formed.

Figure 7 is a similar view of another part of the table leg.

45 Figure 8 is a view in horizontal section taken on the line 8—8 of Figure 3 looking in the direction indicated by the arrows and drawn to an enlarged scale.

Figure 9 is a fragmentary view in vertical section taken on the line 9—9 of Figure 8.

50 Figure 10 is a view in transverse section taken on the line 10—10 of Figure 3 looking in the direction indicated by the arrows.

Figure 11 is an enlarged fragmentary view in vertical section taken on the line 11—11 of Figure 3, looking in the direction indicated by the arrows.

Figure 12 is a detailed view in side elevation of a locking member, one of which is associated with each of the table legs.

Figure 13 is a view in top plan of a swinging leaf supporting bracket with which the table is 5 equipped.

Figure 14 is a view in top plan of a limiting latch associated with said bracket.

Figure 15 is a view in edge elevation of said latch member.

Figure 16 is a perspective view of a limiting stop member for said bracket.

Figures 17 and 18 are detailed views illustrating the relation of the latch and stop members to said bracket member, respectively, and 15

Figure 19 is a fragmentary perspective view of the upper end of the lower leg section 13.

Figure 20 is an enlarged perspective view of one of the leg members removed from the top.

Fig. 21 is a detail side elevation of the leg shown 20 in Fig. 20.

Figure 22 is an enlarged fragmentary sectional view taken on the line 22—22 of Fig. 20.

In its illustrated embodiment, the table of my invention comprises a table top 1, side members 2, and end members 3 forming a substantially rectangular open bottom structure. The top 1 may be secured to the side and end members by any suitable means, for instance, as by brackets 3'.

A pair of inner leaves 4 are suitably hinged to the side members 2, as at 5, and a pair of outer leaves 6 are hinged, as at 7, to the outer side edges of the leaves 4 respectively. The leaves 4 and 6 and the hinges 5 and 7 are arranged so that said leaves may be swung upwardly to form butt joints therebetween and between the inner leaves and the table top 1. The inner leaves 4 are of a proper width to fold down against the side members 2 with their outer edges flush with the lower edges of the latter so that the outer leaves 6 may be folded under the table parallel with the table top 1. The width of the outer leaves 6 is such that they substantially close the space between the side and end members 2 and 3. At suitable points adjacent their ends and intermediate the same, the leaves 6 are provided with transverse reinforcing cleats 8.

Adjacent each corner of the table are cleats 9 suitably secured to the under side of the top 1 and to the inner sides of the members 3, and to which are hinged, as at 10, corner legs 11 swingable on said hinges to fold up toward the table top 1 in the space between the members 2 and 3. Each leg 11 comprises an upper section 12 and a lower section 13 telescoping in the 55

upper section, each section being triangular transversely and constructed as follows:

The upper section 12 comprises an outer plate 14 substantially right angular in cross section, 5 an inner substantially flat plate 15, and an angle bracket 17 projecting laterally from the outer plate 14 on one side of said section and including a socket 18 for a purpose presently clear. The legs 11 at opposite ends of the table, 10 are connected together for movement in unison by bars 17' secured in the sockets 18 of the appropriate brackets 17 by bolts 18'. The plate 14 and bracket 17 are formed from a single piece of suitable flat metal, a blank of which 15 is shown in Figure 6, having a lower portion a, provided with converging side edges 16, short edge wings 27 and end wings 28 having purposes presently seen, a portion b, above the portion a, having curvilinear edges 16' and a portion c 20 above the portion b, somewhat reduced in width as compared with the portion b. The portions a, b, and c, are bent along the longitudinal center of the piece of metal, as represented by the dot and dash line d-d in Figure 6, to form the sides 25 of the plate 14 whereby said plate presents a leg substantially of mutton shape as will be clear. Projecting from the upper edge of the portion c, is a flap portion e, adapted to be bent over at right angles to the portion c, along the dotted line f-f, to form a top for the leg section 12 and having a notched edge 19 adapted 30 to be bent over to form a part of the hinge 10. Extending from the flap portion e, is a group of 35 portions g, i, and k, respectively, of a suitable shape for cutting and bending into the form of the angle bracket 17 and socket 18. At suitable points the portions k and g are provided respectively with tabs 20 and apertures 21 in which said tabs are designed to be inserted and bent over to hold the portion k, in shaped position. The portion c, is provided with a flap portion 40 23' designed to be bent on the inside of the section 12 to form a ledge 23 of a triple thickness of the metal for a purpose presently explained. Said portion c, is also provided along one edge thereof, with a wing portion 24, tabs 25 at its opposite edges, and tabs 26 on said wing portion, the former to be bent over the inner plate 15 to attach the latter to the plate 14, as will presently 45 more clearly appear.

The inner plate 15 is likewise formed of a single piece of flat metal, a blank of which is shown in Figure 7, and comprising edge wing portions 29, incut edges 30 at its upper end, and 50 a lower end wing 31. The inner plate 15 is adapted to be bent along the dotted lines 32 and 33 and cut along a line 34 to fit within the outer plate 14. The wings 27 of the plate 14 are then crimped around the lower end of the plate 15, 55 the tabs 23', right, and 25, left of said plate 14 are bent downwardly over the incut edges 30 and the tabs 26 interlocked with the related apertures 21 in the portion g. The portions 28 and 31 are bent, as shown in Figure 9, to form 60 a bead 34' around the lower end of the section 12 for receiving a rubber bearing member 35 upon which the lower section 13 may slide, to prevent the same from being marred by scraping against the inner face of the upper section 12. At its upper end the lower section 13 is 65 formed on at least two sides thereof with a flange 34'' for spacing the upper end of said section from the upper section 12 to further prevent marring of the lower section.

70 The lower section 13 of the legs 11 is formed

75 of a single piece of flat metal bent upon itself, as shown in Figure 10, into transversely triangular shape conforming to that of the section 12 and to provide a central partition 36 in said section 13 and an external longitudinally extending groove 37 tapering equally, with respect to its depth and width, from top to bottom. The plate 15 of the section 12 is provided with pairs of opposed ears 38 to clamp therebetween a strip 39 in which are threaded conically pointed wing 10 bolts 40 for cooperation with the groove 37 to hold the sections 12 and 13 in different adjusted positions. A cap piece 41 is secured to the lower end of the plate 14 of the section 12, in apertures 42 in said plate, to conceal the angle of 15 the section at this point and for ornamental purposes. The lower leg sections are formed at their lower ends with outwardly flaring sockets 13' in which are secured non-skid rubber feet 14'.

20 In forming the upper leg section the first step is to bend the opposite sides of the portion i upwardly as viewed in Figure 6 at right angles to the blank along the dotted lines j-j and n-n. The extreme left hand side of the portion i is then bent along the line m-m at a right angle over the remainder of the portion i which operation turns the portion k over the portion g. In this position of the parts the tabs 20 on the left hand edge of the portion i will 25 be in position to be clinched in the apertures 21 in the right hand edge of said portion to form the socket 18. Next the socket 18 thus formed is bent upwardly on the dotted line h-h at a right angle to the portion g, the adjacent end of the 30 socket 18 being brought to bear squarely upon the upper end of the portion g. Next, both sides of the portion k are bent upwardly at right angles along parallel lines to form the angle bracket 17 which is then bent at its extended 35 point of connection with the portion i with its free end brought into engagement with the socket 18 and secured thereto by insertion of the bolt 18'. In this position the tabs 20 on the portion k can be engaged with appropriate 40 apertures 21 in the portion g and clinched. The wing portion 24 is then bent at right angles to the portion c downwardly as viewed in Figure 6, along the dotted lines indicated in said figure, the tabs 26 bent backwardly, or upwardly at 45 right angles to the wing 24 and the tab 25 left bent downwardly at right angles to the portion b. This operation forms a support 19 for the 50 socket 18 as shown in Figure 11. The portions a, b, and c may now be bent downwardly longitudinally along the dotted line d-d to form a right angle therewith. Next the portion e is bent on the line f-f and similarly the portion g is bent along the dotted line p-p thus bringing the adjacent left hand edges of the portions c 55 and g together. The wing portion 24 will now be underneath the adjacent edge of the portion g and the tabs 26 may be inserted into and clinched in appropriate apertures 21 in the portion g. The flap portion 22 is now turned over at a slight angle on the dotted line, indicated in Figure 6, to bring its upper edge into engagement with and slightly under the projecting edge of the portion e. The latter is then clinched downward over the flap 22 thus forming a bevel edge 60 opposite the hinged portion 19 affording necessary clearance for folding and unfolding the table leg. The hinged portion 19 is bent downwardly in right angles to the portion e on the 65 70 75 75

dotted line shown in said figure to form the hinge eyelets.

The next step is the formation of the plate 15 and its assembly with the plate 14. The plate 15 is bent along the dotted lines shown in Figure 7 and cut on the line 34 to conform to the shape of the partially shaped upper section 12 and placed in the latter with the upper and lower ends of said sections directly aligned thus bringing all corresponding parts in the proper position. The edge wings 27 of the plate 14, are then bent over the corresponding edges of the plate 15 and the tab 23' of the plate 14 bent downwardly over the shoulder 30 of the plate 15. The tab 25 right is now bent over the adjacent upright edge of the plate 15. The lower end wings 28 and 31 may now be bent into the proper shape to hold the rubber bearing member 35 and the ends of the wing 28 folded over the wing 31 for subsequent welding thereto. The cap piece 41 is next secured by suitable tabs thereon in the apertures 42 in the plate 14 by welding said tabs. The strip 39 is secured between the ears 38 to receive the wing bolts 40 for incorporation with the groove 37 in the lower section 13. This completes the formation of the upper section 12 of the table leg.

Associated with the legs 11 are locking members 43. Each locking member comprises a channel plate of flat metal hinged to the under side of the table top 1, as at 44, for movement about an axis at a right angle to that of the hinge 10, and above the latter, so that said member 43 may be swung to an unlocking position intermediate the leg and the table top when said leg is folded, or, swung in the opposite direction to position its lower end over the beforementioned ledge 23 of the leg section 12. Said member 43 is provided with a lip 45 for cooperation with the ledge 23 in the locking position of said member. Each locking member 43 is provided with a latching element 46 pivoted in the sides 41 of said member 43 and designed, in the locking position of the member, to project through the adjacent side member 2 through a bayonet slot 48 in a plate 49 secured to said member 2 in which slot the element 46 is manually manipulative to latch the locking member in locking position. The locking member 43 is formed of a single piece of flat metal, a blank of which is shown in dot and dash lines in Figure 12, and comprising a main portion *h*, side wing portions *i*, designed to be bent into right angular relation to the portion *h* and flap portions *j*, designed to be bent and crimped upon themselves to provide reinforced bearings for the latch element 46.

Referring to the use of the invention as so far described, assuming the parts to be in unfolded position, to vary the height of the table it is merely necessary to manipulate the wing bolts 40 to elongate or shorten the legs 11 as desired, by moving the section 13 in section 12 and adjusting the said bolts to clamping positions. To fold the legs the locking members 43 are first released by manipulating the latching elements 46 so that the latter may be withdrawn through the plates 49 and side members 2. Said members 43 are then swung toward the table top 1 to unlatching position. The legs 11 at one end of the table are then swung, inwardly of the table, on their hinges 10 into engagement with the table top 1, and the other legs are then similarly swung into engagement with the first folded legs, all as shown in Figure 4. The leaves 4 and 6 after being released from extended position, as

presently described, are then swung to position the inner leaves 4 along side of the members 2 and to fold the outer leaves 6 under said side members 2 and the end members 3, as shown in Figure 2. Said leaves 6 are then latched in folded position by means of hooks 50 pivotally connected to a central cleat 51 on the under side of the table top 1 and adapted to engage eyelets 52 in the leaves 6. Preferably the hooks 50 are arranged to extend in crossed relation when engaged with the eyelet 52 so that they are more easily manipulated through a space between the folded leaves 6. When not so used the hooks 50 may be engaged with eyelets 50' in the sides 2 of the table to act as braces between said sides 15 and the top 1. To add strength to the hooks 50 they are covered with a sheet metal wrapper 52'.

Upon each side of the table is a pair of leaf supporting brackets 53, respectively, pivotally mounted, as at 54, on the side members 2 to swing flat against the latter in end to end position or outwardly into extended positions beneath the leaves 4 and 6. Each bracket 53 is formed of a single piece of metal, substantially triangular in shape, bent upon itself to provide hinge eyelets 55 and opposed channeled sections 56 connected together at their free ends by an ear 57 on one portion 56 projecting through a larger aperture 58 in the other portion and a second ear 59 projecting from said one portion through an aperture 60 in said other portion. Connected to the ear 57 of one bracket of each pair is a hook member 61 adapted in its idle position to rest upon the ear 59 of said bracket, as shown in Figure 13, and designed to hook into the ear 57 of the other bracket of the pair to hold said brackets in outwardly swung position. The brackets 53 are of the requisite length so that when they are swung at right angles to the members 2 they will support the leaves 4 and 6 in extended position and the hooks 61 are of a proper length so that the brackets of each pair may be coupled together in an intermediate position in which they extend to the outer edges of the leaves 4 only so that the leaves 6 may occupy pendant position as shown for instance in Figure 1. By virtue of this arrangement the width of the table may be increased by the width of either one or both of the leaves 4 or by either one or both of said leaves 4 and one of the leaves 6, or by the over all width of all of the leaves. It may be stated that in their fully extended position the brackets 53 are designed to underlie the beforementioned end cleats 8 and to be latched thereto by the following means. Secured to the said end cleats 8 are spring clips 62, Figures 14 and 15, each having a resilient tongue 63 designed to enter the beforementioned aperture 58 in the bracket 53 with a snap action. Associated with each bracket 53 is a stop member 64 secured to the cleat 8 with which the bracket is related and having a depending rigid tongue 65 designed to enter an aperture 66 in the bracket. The purpose of this arrangement is to prevent the leaves 4 and 6 from buckling upwardly at the joints therebetween. It will be understood of course that the relation of the hinges 54 of the brackets 53 to the hinges 5 of the leaves 4, or vice versa, is such that when said brackets are swung flat against the side of the table, the leaves 4 may be folded substantially flat against said sides.

The manner in which the brackets 53 and the leaves 4 and 6 are manipulated to fold and unfold the table will, it is thought, be clear from

the foregoing and therefore requires no further explanation.

The foregoing is a detailed description of a preferred embodiment of my invention, but it is to be understood that right is herein reserved to modifications and changes falling fairly within the scope of the claims appended hereto.

What I claim is:

1. A table leg comprising, upper and lower telescoping sections of triangular shape in cross-section, the upper section including a sheet metal plate bent upon itself into right angular formation to form two side walls for said section and a flat sheet metal plate secured between said side walls to form the other side wall of said section, hinge eyelets carried by the upper section below the upper end thereof, the lower section comprising a single piece of sheet metal bent upon itself to form the side walls of said lower section and a longitudinally extending strengthening partition in said section extending across the same.

2. A table leg comprising, upper and lower telescoping sections of triangular shape in cross-section, the upper section including a sheet metal plate bent upon itself into right angular form to provide two side walls for said section, hinge eyelets carried by the upper section, and a flat sheet metal plate secured between said side walls and forming the other side of said section, the lower section comprising a single piece of sheet metal bent upon itself to form the side walls of said lower section and a longitudinally extending central groove in one side wall thereof, and a strengthening partition in said lower section extending from said groove across said section.

3. A table leg comprising, upper and lower telescoping sections of triangular shape in cross-section, the upper section including a sheet metal plate bent upon itself into right angular form to provide two side walls for said section, hinge eyelets carried by the upper section, and a flat sheet metal plate secured between said side walls and forming the other side of said section, the lower section comprising a single piece of sheet metal bent upon itself to form the side walls of said lower section and a longitudinally extending central groove in one side wall thereof, and a strengthening partition in said lower section extending from said groove across said section, said upper section having opposed ears thereon, a block clamped to said section by said ears, and a set screw threaded into said block and through said upper section for cooperation with the groove in the lower section to secure said sections against telescoping movement.

4. A table leg comprising upper and lower telescoping sections of triangular shape in cross-section, the upper section including side walls, a top portion provided with hinge eyelets, and a laterally projecting bracket comprising angularly related hollow arms and a socket therein, and all formed of a single piece of sheet metal bent upon itself.

5. A table leg comprising upper and lower hollow telescoping sections of triangular form in cross-section, the upper section having an internal groove around its lower end, hinge eyelets carried by the upper section below the upper end thereof, and a resilient anti-friction member in said groove and surrounding said inner section.

ALPHA O. HENDRICKS.
